LADY'S STOCKING

Onesime H. Pons, Valdese, N. C., assignor to Pilot
Full Fashion Mills, Inc., Valdese, N. C., a corporation of Delaware

Application July 21, 1953, Serial No. 26,066

Term of patent 14 years

(Cl. D47—7)

To all whom it may concern:

Be it known that I, Onesime H. Pons, a citizen of the United States of America, residing at Valdese, in the county of Burke, State of North Carolina, have invented a new, original, and ornamental Design for a Lady's Stocking, of which the following is a specification, reference being had to the accompanying drawings, forming a part thereof.

The design is characterized by a generally rectangular area extending across the top of the toe portion of the stocking and said generally rectangular area having a lace-like appearance, as shown.

I claim:

The ornamental design for a lady's stocking, substantially as shown and described.
